UNITED STATES PATENT OFFICE.

ADDISON T. SAUNDERS, OF CHICOOEE, MASSACHUSETTS, ASSIGNOR TO A. G. SPALDING & BROS., OF JERSEY CITY, NEW JERSEY, A CORPORATION OF NEW JERSEY.

SHOE-SOLE.

1,330,552.

Specification of Letters Patent. Patented Feb. 10, 1920.

Application filed November 17, 1917. Serial No. 202,545.

To all whom it may concern:

Be it known that I, ADDISON T. SAUNDERS, a citizen of the United States, and resident of Chicopee, Massachusetts, have invented 5 certain new and useful Improvements in Shoe-Soles, of which the following is a specification.

My present invention concerns a boot or shoe sole of the general type disclosed in 10 application for Letters Patent of the United States, filed by me August 7th, 1917, Serial Number 184,951, and particularly to means by which such a composite sole may be attached to the upper of the shoe.

15 The invention consists in the features and combination and arrangement of parts hereinafter described and particularly pointed out in the claims.

In the drawings:

20 Figure 1 is a plan view of a composite rubber sole embodying my invention.

Fig. 2 is a cross sectional view of a portion of the sole.

25 Fig. 3 is a cross sectional view showing how the sole is attached to the upper.

Fig. 4 is a perspective view of an insert piece, which may be used in carrying out the invention.

30 Fig. 5 is a cross sectional view of a mold illustrating how the insert piece may be placed in the composite sole.

Fig. 6 is a cross sectional view of a modification.

Fig. 7 is a view of the sole complete.

35 Fig. 8 is a plan view of a sole having a fabric strip providing the flexible lip, instead of employing a sheet of fabric extending entirely across the sole.

40 Fig. 9 is a sectional view of a portion of a mold with the material making up the sole shown therein, together with the fabric which forms the lips, this view illustrating the manner of providing this lip standing perpendicular to the upper surface of the sole.

45 Fig. 10 is a view similar to Fig. 9 showing the manner of arranging the lip at a different position relative to the sole from that shown in the other figures.

50 In the application above mentioned I disclose a sole composed of rubber and fibrous material, one feature of which is a layer of fabric on the attaching side of the sole covered by a thin layer of rubber.

55 In carrying out my invention in one form

this fabric layer on the attaching side of the sole with its coating of rubber is an element, in that I provide a slit or channel along the edge of the sole just beneath this layer to thus provide a flange or attaching lip or strip composed of rubber and the reinforcing fabric. The depth of this channel, which I form in the edge of the sole near its upper surface, is indicated in Fig. 1 by the dotted lines and the lip portion thus provided is designated by the numeral 1. This lip is also indicated in Fig. 2 at 1 and the thin coating of rubber on the upper and lower surfaces of the fabric of this lip is indicated at 1' and 1'', and the channel or slit 60 which provides this lip 1 is indicated at 2. 3 indicates the body of the sole, and the dotted line indicates the lower limit or extent of the thin rubber coating on the fabric 1' which constitutes the main part of the 65 layer on the attaching side of the sole and by reason of the location of the slit 2 this fabric layer constitutes the main body of the lip 1, which, as above-mentioned, is made up of the fabric layer, together with its thin 70 rubber coating on the upper and lower side.

In Fig. 3 I show how a sole having the fabric reinforced projecting lip is attached to the leather upper. In this figure, 5 is the welt strip attached to the upper 6, and inner 85 sole 7 by stitching at 8, this being ordinary practice in leather shoes.

My improved sole is attached to this upper by means of the welt 5 and the lip 1 of my improved composite sole, the attachment 90 being effected by stitches at 5' passing through the welt 5 and the lip 1, the channel 2 permitting this stitching to be laid in place, it being noticed that this stitching does not pass through the entire sole, but 95 only from the channel 2 through the lip 1 and the welt 5. The channel or slit in the edge of the sole may be formed after the sole is molded with its fibrous material incorporated therein, or this channel to provide the attaching lip 1 may be produced during the molding of the sole, as will be hereinafter described.

In Fig. 4 I show an insert piece of fabric of dish-form having perforations through 105 which the compound may pass to unite the said compound lying on opposite sides of the said insert piece. This insert piece may be combined with or incorporated with the rubber sole by a molding operation, as in- 110

dicated in Fig. 5, in which 8 is the top plate of the mold having a shallow recess at 8' to receive the edge 1^a of the insert piece 1^a, this edge overlying a flange or rib 9^a which is formed with or attached to the middle section 9 of the mold, the said flange or rib being tapered in cross section to present a knife-edge directed toward the interior of the mold. 10 indicates the bottom plate of the mold and 11 indicates dowel pins by which the sections are properly positioned relative to each other. The sole is built up and molded in the appliance just described and illustrated in Fig. 5, the sole portion being indicated at 3, 3, and lying on opposite sides of the dish-shaped member 1^a. The knife edge projection 9^a provides for the formation of the channel in the edge of the sole, leaving the lip designed for attachment to the upper provided by the overlying projecting edge of the insert piece, as indicated at 1^a. The dish-shaped piece, as above described, is perforated so that the rubber compound lying in these perforations in the completed article will unite the portions of the sole lying on opposite sides of the insert piece. In laying up the sole in the mold of Fig. 5 I prefer to invert the mold from the position shown and where the embossed fabric of the dish-shaped illustrated in Figs. 4 and 5 is employed I first lay down on the plate 8 the section of the sole indicated in Fig. 5 above the mold section 9. The fabric insert piece 1^a is next laid in position and adhered to the sole section 3, laid in place and the edge of the insert piece is laid into the recess 8'. It may be noted here, however, that the first section of the sole, which is laid in place, is of somewhat less width than the recess of the mold, and consequently any suitable score mark may be formed or provided on the mold plate 8 to enable the first section of the sole to be laid accurately in place. After the insert piece 1^a is laid in position the mold section 9 is next placed, being guided by the dowel pins and the stock for the other portion of the body of the sole indicated by the numeral 3 lying below the insert piece is next laid in position and upon the knife edge flange 9^a and finally the mold member 10 is put in place and curing is then performed in a press in the usual manner.

In the case of a stiff shanked sole the portion of the body of the sole first laid in position may consist of a plurality of compounds of the desired character for the different parts of the sole and the fabric layers described in my application above mentioned when used are of course placed in position in the laying up operation. The other part of the stock, which is laid on after the insert piece 1^a is placed in position 65 may be made up in its different portions

from harder and softer stocks, as may be desired.

As shown in Fig. 6 the attaching lip may be provided by doubling the fabric or rolling it over upon itself into a form known as "piping." This form of the invention may be made up of a plurality of layers of the coated fabric instead of a single one. Further, instead of employing a layer of fabric extending over the entire width of the sole I may employ a strip embedded in the rubber compound and extending only part way across the width of the sole, this strip providing the lip, because of the fact that the channel above mentioned exists below it. This strip is indicated in Fig. 8 at 1^b extending in to the dotted line x, the lip being designated by the numeral 1, as above. This strip is formed by cutting out the central portion of the fabric layer. The cutting out is done before laying up the parts, and is well within the point where the lip is unattached, or in other words well within the dotted line y.

The sole, as above described, may be cemented to the welt 5 of the shoe upper or to the upper itself, or to a member—a first layer of other material than rubber—attached to the shoe, and the stitching employed as an additional fastening means. The projecting attaching lip may consist of uncoated fabric, but I prefer to cover with a suitable rubber compound and then frictioned in the usual manner. The compound for the coating may be of any character which affords the required degree of flexibility together with other qualities matching the portions of the sole with which it is united.

It is not necessary that the shank member be all of one piece throughout the shank and tread portions of the sole, the portion coming in contact or in close with a red thread, as might be the case in a sole of my stiff shanked type, illustrated in the application above mentioned, may be of such a red compound, and the portion uniting with the black shank portion may be of that color.

In any case, however, this attaching lip must not comprise a hard curing compound similar to that used in my stiff shanked sole, but on the contrary a compound of the desired degree of softness or flexibility must be employed which unites with the hard compound satisfactorily in curing.

Instead of perforating the insert piece, such as shown in Figs. 4 and 5, an open-mesh weave may be employed to permit the rubber to unite through it, but a close firm weave of fabric is preferred in order to receive the stitching.

It will be understood from the above that I may provide the attaching strip 1 in different ways and it may be made to rise per-

pendicularly from the face of the sole at the desired distance from the edge and it may be anchored in different ways.

Fig. 9 illustrates how the lip 1 may be made to extend up perpendicularly from the face of the sole. In this figure 1^a is the insert piece, and 1 the lip thereof. 3 indicates the body portions of the sole as in the previous figures. 10 is the mold member, and 10 8', 8'' are also mold members, these latter members having between them the recess 12 for receiving the perpendicular lip. 11 indicates the dowel pin and 9^x is a mold portion corresponding substantially to the member 9 of Fig. 5, but attached to one of the other mold portions. The recess 12 provides a free fit for the lip portion 1. The coating of soft compound upon the lip and upon the surface of the sole stock as laid up, 20 flows under the heat and pressure of curing into any space in the recess 12 not occupied by the fabric strip.

Fig. 10 shows the mold modified at the meeting point of the members 8', 8'', to cure 25 the strip at a different angle from that shown in Fig. 9. The formation of the lip in the positions indicated in Figs. 9 and 10 will enable the sole to be attached to an upper directly as in the case of a boot or shoe 30 comprising rubber, by cementing the lip directly to the upper and recurring therewith to get a perfect union.

After stitching the lip to the upper the channel 2 may be closed by cementing its 35 upper and lower walls together.

In Fig. 7 I show a complete sole in edge view embodying my invention, this sole being like that described in the above mentioned application, having a stiff shank portion *a* and a flexible tread portion *b*. At *c* is indicated in dotted lines the layers of reinforcing fabric extending throughout the shank and terminating at different points in echelon within the tread portion and the 45 attaching lip is indicated at 1 extending along the upper edge of the sole throughout both the length of the stiff shank portion and the flexible tread part, said lip in all

parts being of such flexible character that it is adapted for attachment to the leather 50 upper.

This sole may embody all the features described in said application in addition to the attaching lip.

What I claim is:

1. A rubber sole having a channel in its edge near its upper surface with an attaching lip forming the upper wall thereof, said lip comprising fabric extending inwardly beyond the bottom of the channel and 60 united with the rubber compound of the main body of the sole, substantially as described.

2. A rubber sole having a channel in its edge near its upper surface with an attaching lip forming the upper wall thereof, said lip comprising fabric coated with rubber extending inwardly beyond the bottom of the channel and united with the main body of the rubber compound of the sole.

3. A rubber sole having a sheet of fabric vulcanized therewith, said fabric having an unattached flexible extension overlying a portion of the sole leaving a channel between itself and the underlying portion of 75 said sole and thereby providing an attaching lip, substantially as described.

4. A sole for a boot or shoe having a tread and a relatively stiff shank both comprising vulcanized rubber and an attaching 80 lip extending along the upper portion of the sole and flexible both along the stiff shank and along the tread, substantially as described.

5. A sole for a boot or shoe having a 85 tread and a relatively stiff shank both comprising vulcanized rubber and an attaching lip extending along the upper portion of the sole and flexible both along the stiff shank and along the tread, said lip comprising an 90 extension of fabric vulcanized with the shank and tread portions of the sole, substantially as described.

In testimony whereof, I affix my signature.

ADDISON T. SAUNDERS.
